UNITED STATES PATENT OFFICE.

WILLIAM S. MASON, OF MAYFIELD, NEW YORK.

ELECTRIC-LIGHTING SYSTEM.

1,273,258.

Specification of Letters Patent. Patented July 23, 1918.

Application filed June 28, 1915. Serial No. 36,625.

To all whom it may concern:

Be it known that I, WILLIAM S. MASON, a subject of Great Britain, residing at Mayfield, county of Fulton, and State of New York, have invented certain new and useful Improvements in Electric-Lighting Systems, of which the following is a specification.

The invention relates to such improvements and consists of the novel construction and combination of parts hereinafter described and subsequently claimed.

Reference may be had to the accompanying drawings, and the reference characters 15 marked thereon, which form a part of this specification. Similar characters refer to similar parts in the several figures therein.

Figure 1 of the drawings is a diagrammatic view of my improved electric-lighting 20 system, showing a top plan view of the switch-mechanism with the cover of the switch-box removed.

Fig. 2 is a side view of the switch-box.

Fig. 3 is a diagrammatic view of the 25 system shown in Fig. 1, showing a bottom plan view of the switch-box.

Fig. 4 is a bottom plan view of the switch-lever and the switch-plates mounted thereon.

Fig. 5 is a cross-section of the same taken 30 on the broken line 5—5 in Fig. 4 through one of the switch-plates.

The invention applies particularly to electric-lighting systems for automobiles or similar vehicles provided with a dynamo 35 (or magneto), and also with an electric battery, from either of which sources a supply of electricity can be obtained for a plurality of electric lamps.

In automobiles so provided the voltage of 40 the electric current from the dynamo is ordinarily much greater than, and in substantially multiple ratio to, the voltage of the current from the battery; and with lighting-systems heretofore employed in 45 such automobiles, it has been impossible to use interchangeably for operating the electric lamps the current from the battery and the current from the dynamo.

The principal object of the present invention is to provide means whereby elec-

tric lamps of an automobile, or the like, can be operated interchangeably by an electric-battery, or by a dynamo, the voltage of the current from which is in substantially multiple ratio to the voltage of the current from 55 the battery.

In carrying out my invention I employ a plurality of electric lamps of substantially the same resistance, whose total resistance bears to their individual resistance the same 60 ratio that the voltage of the current from the dynamo bears to the voltage of the current from the battery; and I provide means for connecting said lamps, at will, either in series with the dynamo or in parallel with 65 the battery.

Referring to the drawings wherein the invention is shown in preferred form, and more or less diagrammatically, 1 and 2 are a pair of incandescent electric lamps of 70 substantially the same voltage; 3 is an electric-battery, which may be of any known form, preferably a storage-battery or a dry battery, the voltage of the current from which battery corresponds with the resistance 75 of the individual lamps, 1 and 2, and 4 is a dynamo (or magneto), the voltage of the current from which is twice that of the voltage of the current from the battery, 3, the voltage of the dynamo thus corresponding 80 with the total resistance of both lamps, 1 and 2.

I have shown in the drawings a preferred form of switch-mechanism for carrying out my invention comprising in part a box, 5, 85 adapted to be attached by means of screws or bolts inserted through apertures, 6, to a suitable support, such as the dashboard of an automobile, said box having a cover, 7, and being provided with a laterally open 90 slot, 8, within which the switch-lever, 9, is adapted to play.

Mounted upon the switch-box are nine switch-contacts, 10, 11, 12, 13, 14, 15, 16, 17, and 18.

Certain of these switch-contacts are electrically connected with one another by wires on the back of, or beneath the bottom of, the switch-box, as follows, as shown in Fig. 3:

Switch-contact, 11, with switch-contact, 12, by wire, 19; switch-contact, 13, with switch-contact, 17, by wire, 20; and switch-contact, 14, with switch-contact, 15, by wire, 5 21.

The switch-contact, 10, is connected by wire, 22, with one pole of the dynamo, the other pole of the dynamo being connected with ground at 23.

10 The switch-contact, 16, is connected by wire, 24, with one pole of the battery, the other pole of the battery being connected with ground at 25.

The switch-contact, 18, is connected with 15 ground at 26.

Wires, 27, connect the terminals of the lamp, 2, respectively with the switch-contacts, 12 and 13, and wire, 28, connects the switch-contact, 15, with one terminal of the 20 lamp, 1, the other terminal thereof being connected with ground at 29.

The operating-mechanism of the switch comprises a switch-lever, 30, pivotally mounted at 31 upon the bottom of the 25 switch-box and adapted to play within and project out through the slot, 8, its projecting end forming a handle.

The switch-lever, 30, is formed of insulating material and carries a pair of 30 switch-plates, 32 and 33, arranged on opposite sides of its pivot, 31.

The switch-contacts are so arranged in 35 groups that in one extreme position of the switch-lever, the switch-plates, 32 and 33, electrically connect with one another the necessary switch-contacts to connect the lamps, 1 and 2, in series with the dynamo, and in the other extreme position of the 40 switch-lever, said switch-plates, 32 and 33, electrically connect with one another the necessary switch-contacts to connect the lamps, 1 and 2, in parallel with the battery, 3.

45 Thus when the switch-lever is in its extreme position at the left, indicated by dotted lines, 30^a, in Fig. 1, the switch-contacts, 10 and 11, are connected together by switch-plate, 32, and the switch-contacts, 13 and 14, are connected together by the switch-plate, 33, the current thus passing from the 50 dynamo through wire, 22, to switch-contact, 10, thence through switch-plate, 32, to switch-contact, 11, thence through wire, 19, to switch-contact, 12, thence through wires, 55 27, and lamp, 2, to switch-contact, 13, thence through switch-plate, 33, to switch-contact, 14, thence through wire, 21, to switch-contact, 15, thence through wire, 28, and lamp, 1, to ground at 29.

60 When the switch-lever is in its other extreme position at the right, indicated by dotted lines, 30^b, in Fig. 1, the switch-contact, 16, is connected by switch-plate, 32, with both switch-contacts, 12 and 15, and

switch-contact, 17, is connected by switch-plate, 33, with switch-contact, 18, the current thus passing from the battery, 3, through wire, 24, to switch-contact, 16, and thence in parallel through switch-plate, 32, to switch-contacts, 12 and 15, the divided current then passing from switch-contact, 15, through wire, 28, and lamp, 1, to ground at 29, and from switch-contact, 12, through wires, 27, and lamp, 2, to switch-contact, 13, thence through wire, 20, to switch-contact, 75 17, thence through switch-plate, 33, to switch-contact, 18, and thence to ground at 26.

The lamps can thus be supplied either from the dynamo or from the battery with 80 electric-current at a voltage corresponding with the resistance offered by the lamps.

The lamps can thus be operated from the dynamo, while the engine of the automobile is running, and the lamps are in proper condition. 85

When the engine is not running, both lamps, if in proper condition, can be operated from the battery; while, if either one only of the lamps is out of order or broken, the other can, nevertheless, be operated from the battery; or when the car is standing idle, one only of the lamps can be operated from the battery as a signal-light, while the other lamp can be disconnected. 90

95 What I claim as new and desire to secure by Letters Patent is:

In an electric-lighting system and in combination, a pair of electric lamps of substantially equal resistance; a dynamo of a 100 voltage-capacity corresponding with the combined resistance of both lamps, one terminal of said dynamo being connected with ground; a battery of a voltage-capacity corresponding with the resistance of the individual lamps, one terminal of the battery being connected with ground; and switch mechanism having a contact connected with the other terminal of said dynamo, a contact connected with the other terminal of said battery, a contact connected with one terminal of one of said lamps, a contact connected with the other terminal of said lamp, a contact connected with one terminal of the other lamp, the other terminal of said last-mentioned lamp being connected with ground, said switch mechanism having means including a movable member whereby in one position of the movable member its said contact connected with ground is also connected with one of the contacts in connection with said first-mentioned lamp, and the contact connected with the battery is also connected with the contacts respectively in connection with the second-mentioned lamp and the other terminal of the first-mentioned lamp, and in another position of said movable 110 115 120 125

switch-member the contact in connection with the dynamo is also connected with the contact in connection with one terminal of the first-mentioned lamp, and the contact 5 in connection with the other terminal of the first-mentioned lamp is connected with the

contact in connection with the second-mentioned lamp.

In testimony whereof I have hereunto set my hand this 18th day of June, 1915.

WILLIAM S. MASON.
